UNITED STATES PATENT OFFICE.

JOHN W. ODLIN, OF WORCESTER, MASSACHUSETTS, ASSIGNOR, BY MESNE ASSIGNMENTS, TO THE CHASE NATIONAL BANK OF THE CITY OF NEW YORK, TRUSTEE, OF NEW YORK, N. Y.

ADVERTISING CARD.

Application filed November 20, 1924. Serial No. 751,111.

To all whom it may concern:

Be it known that I, JOHN W. ODLIN, a citizen of the United States, residing at Worcester, in the county of Worcester and State of Massachusetts, have invented a new and useful Advertising Card, of which the following is a specification.

The principal object of this invention is to provide an advertising card that can be carried and delivered in a flat condition so that it will not be bulky and will have mounted thereon a sample of the goods; and also to provide a means for attaching the sample in what seems to be the most simple, practical and inexpensive manner possible. The card also is of such a nature as to protect any projecting or cut edges or points on the article so that they will not catch in the pockets or clothing.

Other objects and advantages of the invention will appear hereinafter.

Reference is to be had to the accompanying drawings; in which

Fig. 1 is an inside view of the card laid out flat without the advertised article;

Fig. 2 is a similar view of the inside of the card showing the article that is being advertised in its position thereon;

Fig. 3 is an end view of the complete article folded up as it is transported and packed; and

Fig. 4 is an outside view.

The card itself consists of a sheet 10 of paper or cardboard of any desired thickness provided with a longitudinal fold 11 at the center. This constitutes a folder which can have advertising or directions on all four of its pages, as indicated. The card is provided with two perforations 12 lying in the fold. These perforations can conveniently be small circular holes but are made of such size and shape as is necessitated by the article to be employed in the folder.

The article to be advertised may be of any kind so long as it is flat or substantially so. In the present case I have shown a piece 14 cut from a wire fence for the purpose of exhibiting and advertising a fence of a particular character. This fence has either at the top or bottom a straight margin wire 15. This is cut off to a length greater than the distance between the two holes 12 and 55 inserted in the holes from the interior so as to project at the rear. The rest of the wire

14, of course, is thus anchored in position in the folder to which it is pivoted and this furnishes a most easy and convenient way of exhibiting the goods. Where the ends of the wire 15 project through the holes at the rear they will lie along the outside of the folder 10 and constitute no projections that are likely to cause trouble in the use and exhibition of the sample. The article sets into the crease when the folder is folded so as to prevent folding at any other point. The two leaves protect it throughout.

The sample is not intended to be taken out of the folder but to be retained therein so that the advertising directions and the like will always accompany the sample and will not ordinarily become separated therefrom. Thus it constitutes not only a means to exhibit a sample for the time being but also serves to keep the manufacturer's explanation with the sample where they are prominently displayed so that the advertising is at its full efficiency even if the sample lies around an office a long time. Furthermore, the fact that the sample lies flat on the card can be taken advantage of to directly point out the good points of the article, as is indicated by a line of lettering 17 which can be used to point out some feature about the article located at the same point as the lettering.

Although I have illustrated and described only a single form of the invention, I am aware of the fact that modifications can be made therein by any person skilled in the art without departing from the scope of the invention as expressed in the claims. Therefore I do not wish to be limited to all the details of construction herein shown and described, but what I do claim is:—

1. As an article of manufacture, an advertising card consisting of a piece of sheet material centrally folded to form a simple folder and provided with two perforations therethrough along the line of said fold spaced widely apart, and adapted to have an article to be advertised having a pair of oppositely projecting points extending through said perforations in opposite directions and in alignment with each other, whereby the article is pivotally mounted on the folder.

2. As an article of manufacture, an advertising card consisting of a piece of sheet material folded to form a simple folder and

provided with perforations therethrough in the fold spaced widely apart, and adapted to have a flat article of wire to be advertised having a pair of oppositely projecting points extending through said perforations in opposite directions and in alignment with each other, whereby the article is pivotally mounted on the folder.

3. As an article of manufacture, a folded advertising card provided with perforations

through the fold and adapted to have an article to be advertised secured to the card by passing through said perforations, the folder having advertising matter on the several pages relating to the article held 15 thereon.

In testimony whereof I have hereunto affixed my signature.

JOHN W. ODLIN.
